G. S. GREEN

EMERGENCY STOP FOR SPRINKLER HEADS

Filed July 23, 1924

George S. Green
INVENTOR
BY Victor J. Evans

WITNESS:

John Donovan

ATTORNEY

UNITED STATES PATENT OFFICE.

GEORGE S. GREEN, OF AURORA, INDIANA.

EMERGENCY STOP FOR SPRINKLER HEADS.

Application filed July 23, 1924. Serial No. 727,763.

To all whom it may concern:

Be it known that I, GEORGE S. GREEN, a citizen of the United States, residing at Aurora, in the county of Dearborn and State of Indiana, have invented new and useful Improvements in Emergency Stops for Sprinkler Heads, of which the following is a specification.

In many buildings use is made of a sprinkling system for extinguishing a fire, which system includes a plurality of sprinkling heads communicating with and supported by a water supply pipe, each head having a plug valve which prevents the escape of water, the valve being automatically released when its retaining means is subjected to heat. It frequently happens that one or more of these valves are automatically unseated, and the water continues to flow from said heads until the supply is cut off. If the sprinkling system is in a place remote from the main water valve the water supply cannot be cut off soon enough to prevent damage to the stock or merchandise in the room by water.

It is therefore the purpose of this invention to provide a device which can be quickly and conveniently associated with each sprinkling head to stop the flow of water within a few seconds.

In carrying out the invention, it is my purpose to provide a substantially wedge shaped element designed to be inserted within the sprinkling head and subsequently driven therethrough an appreciable distance to cause the said elements to effectively close the water outlet opening of said head, the invention residing in the construction, combination and arrangement of parts as claimed.

In the drawings forming part of this application, like numerals of reference indicate similar parts in the several views, and wherein:

45 Figure 1 is a side elevation of the device showing how it is initially associated with a sprinkling head.

Figure 2 is a top plan view of the wedge shaped element.

50 Figure 3 is a sectional view taken on line 3—3 of Figure 2.

Figure 4 is a plan view of the handle and ram rod.

55 Figure 5 is a sectional view taken on line 5—5 of Figure 4.

Figure 6 is a fragmentary view of one of the guides for the ram rod.

The device forming the subject matter of this invention comprises a handle 10 which preferably consists of an elongated piece of wood, which may vary in size without departing from the spirit of the invention. Secured to this handle adjacent one end are spaced U-shaped elements 11 which are arranged to straddle the handle and having their cross pieces spaced from the upper surface thereof to receive the support for the wedge shaped member above referred to. Also secured to the upper side of the handle is a strip of resilient material indicated at 12, one end of which is offset as at 13 to be received by the clamps 11, the offset extremity being spaced from the handle as shown in Figure 1, inasmuch as the support 14 for the wedge shaped member is adapted to be positioned between this offset extremity 13 of the strip 12 and the handle 10, as shown in Figure 1. The strip is used to assist in holding the wedge support 14 properly associated with the handle for use.

The wedge shaped member is indicated at 15, and is mounted upon its support 14, and held positioned thereon by headed fastening elements 16. There are preferably two of such fastening elements threaded into the support 14, the elements being passed through a longitudinal slot 17 so that the wedge shaped member can be moved longitudinally of its support in a manner and for a purpose to be presently described.

Arranged above and secured to the wedge shaped member is a metallic band 18 to protect the member from wear by contact with the sprinkling head, the wedge shaped member being preferably constructed of wood.

Secured to the underside of the support 14 is a length of rubber or other relatively soft material indicated at 19 which serves as a gasket to make a fluid tight connection between the said support and the water outlet opening of the sprinkling head, when the wedge shaped member is arranged in position for use.

The wedge shaped member is designed to receive a metallic plate 15' which is also slotted to accommodate the fastening element 16, the heads of the fastening elements reposing on this plate to permit the wedge shaped member to slide freely as will be readily understood.

Supported upon the handle are spaced

brackets 20, each of which is formed with an opening 21 as shown in Figure 6, and slideable through these brackets is a ram rod 22 which is preferably provided with a stop 5 pin 23 to limit the movement of the rod in one direction. This rod is utilized to drive the wedge shaped member through the sprinkling head 24 after the said member has been positioned within the head as shown 10 in Figure 1.

In practice, assuming that the valve of the sprinkling head has been removed therefrom, and it is desired to stop the flow of water through said head, it is only necessary 15 to arrange the support 14 of the wedge shaped member 15 within the clamps 11 carried by the handle 10. After the parts have been thus associated, the wedge shaped member is slipped within the sprinkling member 20 24 as shown in Figure 1, and the ram rod 22 subsequently reciprocated to strike the end of the wedge shaped member 15, and thus wedge this member within the opening of the sprinkling head. As the member 25 15 is wedged within said head the gasket 19 is compressed against the head directly above the water outlet opening thereof, and seals or closes this opening to cut off the flow of water. The wedge shaped member remains 30 in this position until the main water supply valve of the water system can be closed, after which the wedge shaped member can be moved from the sprinkling head, and the latter then supplied with another valve. 35 After the wedge shaped member has been driven into the sprinkling head, the handle 10 can be removed therefrom, and subsequently used in conjunction with another wedge shaped member if the circumstance 40 should require its use.

While it is believed that from the foregoing description, the nature and advantages of the invention will be readily apparent, I desire to have it understood that I do not

limit myself to what is herein shown and described, and that such changes may be resorted to when desired as fall within the scope of what is claimed.

What I claim is:

1. A device of the character described comprising a handle, inverted U-shaped members secured to the handle and having their intermediate portions spaced therefrom, a wedge shaped member, a support therefore, said support reposing upon the handle and received by the U-shaped members, resilient means interposed between the support and said intermediate portions of the U-shaped members to assist in holding the support fixed with relation to said handle, said wedge shaped member being capable of sliding movement on said support, and a rod slidably mounted on the handle and adapted to move the wedge shaped member in one direction on its support for the purpose specified.

2. A device of the character described comprising a handle, a wedge shaped member, a support therefore including an elongated member reposing upon the handle and projecting beyond one end thereof, means for clamping the support to the handle, said wedge shaped member being longitudinally slotted, headed elements passed through said slot and secured to the support for associating the wedge shaped member with the support for sliding movement thereon, yieldable material secured to the underside of that portion of the support which projects beyond the handle, a metallic member covering the slot of the wedge shaped member, and a ram rod slidably mounted on the handle and adapted to be moved into engagement with the wedge shaped member for sliding the latter in one direction on its support for the purpose specified.

In testimony whereof I affix my signature.
GEORGE S. GREEN.
